UNITED STATES PATENT OFFICE.

ERASTUS S. BENNETT, OF NEW YORK, N. Y.

SCREW-PUMP.

1,271,836.

Specification of Letters Patent.

Patented July 9, 1918.

Application filed April 28, 1917. Serial No. 165,205.

To all whom it may concern:

Be it known that I, ERASTUS S. BENNETT, a citizen of the United States, and resident of New York, N. Y., have invented certain 5 new and useful Improvements in Screw-Pumps, of which the following is a specification.

My invention is an improvement in rotary screw pumps of the type in which a screw 10 form of blade is mounted upon a shaft to rotate in a casing and in proximity to a diaphragm supported in said casing, the purpose being to drive the fluid through the casing under high velocity.

15 The invention is shown in the accompanying drawings, in which,

Figure 1 is a sectional view of a part of a pump casing containing a pair of blades made in accordance with my present improvement and a diaphragm of special construction to coöperate with the said blades in securing a proper pumping or forcing action of the water.

Fig. 2 is a detail sectional view of one of 25 the walls of the spokes in the diaphragm.

Fig. 3 is a cross sectional view through the casing illustrating the propelling blades.

Fig. 3^a is a view of the end of the blade;

Fig. 4 is a view showing an old form of 30 blade.

In these drawings the casing is indicated at 1, within which a shaft 2 is located, being mounted in suitable bearings, the shaft having mounted thereon hubs, one of which is indicated at 3 carrying the pumping or propelling blades 4 which extend from the hub close to the inner side of the casing. These blades are arranged in pairs and between the pairs of blades there is a diaphragm composed of a ring 5 held between sections of the casing, said diaphragm having radial spokes or arms of the form in cross section shown in Fig. 2, that is, these spokes are thickened at their central portion and taper to each 45 edge. The spokes extend from the outer ring 5 to a much longer inner ring 6 arranged close about the hubs carrying the blades, these hubs being formed to interlock as at 7 one with the other. The spokes at their 50 inner ends are of a width, measured along the shaft, equal to the length of the inner ring 6 and from this point they taper in width to the outer ring 5. The propeller blades, instead of being formed as heretofore of screw-shape shown in Fig. 4 are of 55 flat or straight form as indicated in Fig. 1,

and are located at an inclination to the axis of the pump and this inclination conforms to the incline of the tapered spokes 8 of the diaphragm, as shown in Fig. 1.

60

Referring to Fig. 4 an objection exists to this form of blade in that the water will be given a swirling motion to a material degree, which of course indicates a lack of efficiency in the pump.

65

It will be noticed by reference to Fig. 4 that the blades are of large diameter in respect to the diameter of the hub and the tendency is to put the water in circular motion owing to the fact that the angle of the 70 blade at its base or at the hub is much greater in relation to the axis of the blade than the angle at the periphery.

In a 6" blade having a 6" pitch the six 75 inches is gained at the periphery through a travel of about nineteen inches, while at the hub say of 1" in diameter the six inches is gained in a little over three inches of circular travel.

In this old style the angular relation of 80 the base of the blade or that portion adjacent the hub is such to the axis of the pump that the work performed by this portion of the blade is little more than simply to cause a swirling of the water, this effect 85 diminishing as the periphery of the blade is approached.

In the improved blade the parts indicated at X in Fig. 4 are eliminated and the swirling action of the water resulting from the 90 presence of these parts is eliminated in the improved blade shown in Fig. 1, the only swirling effect on the water left in the improved blade is that due to the greatly lessened angle of the periphery, which angular 95 relation continues to the hub, the blade being a perfectly straight plate.

The swirling of the water consumes power and is opposed to the forward movement of the water through the pump and its elimination 100 increases the efficiency of the pump.

It will be noticed that the blade of Fig. 1 rotates in close proximity to the edge of the diaphragm, the spokes of which are shaped to conform to the angular relation 105 of the straight blade and this blade acting close against the diaphragm cuts off the water at the point where the water is moving onward through the diaphragm and where the swirling of the water is resisted 110 by the diaphragm and the blade being of the form shown to eliminate a swirling action on

the water the result will be that the water coming onward through the diaphragm will be impelled onward by the straight flat blade acting thereupon. The suction end of the 5 blade is sharpened to reduce resistance.

One advantage of the form of blade disclosed herein is that it is easier to cast and to finish than the old form and therefore cheapness of production results.

10 What I claim is:

1. A screw pump comprising a casing, a diaphragm within the casing having openings for the passage of water therethrough and a blade rotating in close proximity to 15 the diaphragm and on each side thereof, said blade being in one plane from end to end and inclined in relation to the axis of the pump, said diaphragm having its opposite sides reversely inclined in respect to 20 each other and conforming to the inclines of the blades substantially as described.

2. A screw pump comprising a casing, a diaphragm within the casing having openings for the passage of water therethrough

and a blade rotating in close proximity to 25 the diaphragm, said blade being in one plane from end to end and inclined in relation to the axis of the pump, the said diaphragm having its side adjacent the blade inclined at an angle corresponding to that 30 of the blade, substantially as described.

3. In combination in a pump, a casing, a shaft within the casing and a propelling member having a hub mounted on the shaft and a blade arranged in one straight plane 35 from end to end and inclined to the axis of the hub and a diaphragm within the casing composed of inner and outer rings, the inner ring being longer than the outer ring, spokes connecting the inner and outer ring and 40 tapering in width outwardly from the inner hub to the narrow outer ring, said spokes in cross section being tapered from the center plane of the diaphragm to each end thereof, substantially as described. 45

In testimony whereof, I affix my signature.

E. S. BENNETT.
